Patented Nov. 2, 1965

202,710

GAS LASER

Robert C. Rempel, Los Altos, and Charles E. Jones,
Sunnyvale, Calif., assignors to Spectra-Physics, Inc.,
Mountain View, Calif., a corporation of California

Filed Aug. 18, 1964, Ser. No. 81,344

Term of patent 14 years

(Cl. D26—14)

Des. 202,710

PAGE 2

FIG. 3

FIG. 4

FIG. 5

FIGURE 1 is a left end, top and front perspective view of a gas laser, showing our new design;

FIGURE 2 is a left end, front and bottom perspective view;

FIGURE 3 is a rear elevational view;

FIGURE 4 is a right end elevational view; and

FIGURE 5 is a left end elevational view thereof.

We claim:

The ornamental design for a gas laser, as shown.
